UNITED STATES PATENT OFFICE.

EDWARD W. STODDARD, OF DETROIT, MICHIGAN.

BARREL-HEAD FASTENER.

1,178,964.

Specification of Letters Patent.

Patented Apr. 11, 1916

Application filed December 19, 1913. Serial No. 807,590.

To all whom it may concern:

Be it known that I, EDWARD W. STODDARD, a citizen of the United States, and a resident of Detroit, in the county of Wayne and State 5 of Michigan, have invented a new and Improved Barrel-Head Fastener, of which the following is a specification.

This invention relates to fastening means for securing the heads or other closures used 10 in connection with metal barrels or other containers in position, and its object is to provide a simple and effective device which can be operated to secure or release the removable closure of various forms of receptacles; which fasteners shall be cheap and 15 easily operated, and which shall not be liable to get out of order.

This invention consists in combination with the stationary shoulder on the body 20 portion of the receptacle, of a revolvable wedge mounted on the closure which shall be adapted to engage the shoulder on the body of the receptacle and force the closure against a stationary flange carried by the 25 body of the receptacle, and thereby secure the parts in the desired position.

In the accompanying drawing Figure 1 is a plan and Fig. 2 an elevation of a barrel. Fig. 3 is a plan of the fastening device for 30 the head. Fig. 4 is a section on the line 4—4 of Fig. 3. Fig. 5 is an elevation of the fastening device.

Similar reference characters refer to like parts throughout the several views.

25 The container shown in the drawing has the usual form of a barrel and is preferably constructed of a sheet of metal properly rolled so as to form the usual bilge barrel construction, the ends of the sheet being 40 joined by electric welding if desired. The upper end of the body 1 is preferably formed with a shallow bead 2 as shown in Fig. 4. Fitting within this upper end of the body of the barrel is a ring 3, L-shaped in cross-section, having a continuous flange 4, which 45 ring is held in position by means of the chime 5, which is composed of the outer portion 6 and the inner portion 7 connected together at their upper edges, which portions 50 6 and 7 may be pressed together to lock the ring 3 to the upper edge of the body of the barrel. This chime 5 may be made of great strength and will prevent distortion of the end of the barrel. The head or closure 8 is 55 of such diameter that it can be inserted through the part 7 of the chime. At inter-

vals a series of rivets or pins 9 are securely mounted on the head, and on these pins the locking members 10 are revolvable. The upper ends 12 of these members are preferably 60 polygonal so that they may be engaged by a wrench, and the lower ends are in the form of circumferential wedges 13, whose small ends 14 will pass below the shoulders 15 of the chime. These wedges 13 are cut away 65 at one side, as indicated in Fig. 3. A ring 17 of rubber or other suitable packing may be placed on the flange 4 if desired.

When it is desired to secure the head in position, the locking members 10 are all 70 turned to the position shown in Fig. 3 and the head is then laid on the shelf 4. The locking members are then turned so as to bring the small edge 14 of the wedge 13 underneath the shoulder 15 of the chime, and 75 continued turning in this direction will force the edge of the head 8 firmly against the flange 4, resulting in a very satisfactory locking of the head in position.

It will be apparent that the head or closure may be of any shape or size and that it may be adapted to receptacles of any desired construction. The number, size, proportions and other details of these locking members can all be changed in order to meet 80 the different requirements of the trade in which receptacles are to be used without departing from the spirit of my invention as set forth in the claims.

I claim:

1. In a receptacle, the combination of a barrel having an annular member secured to one end consisting of an inwardly projecting flange and a substantially cylindrical portion in engagement with the edge of the barrel, a reinforcing chime substantially U-shaped in cross-section extending over the edges of the barrel and said cylindrical portion to secure the annular member in position and constituting a continuous shoulder 95 parallel to the flange and spaced apart therefrom, a closure in the form of a disk of less diameter than the chime resting on the flange, a series of pins projecting upwardly from said disk, and a fastening device revolvably mounted on each pin and comprising a cylindrical body substantially tangential to the disk, and a circumferential wedge connected to said body with its ends so disposed that said wedge may be positioned entirely within the circumference of the disk but is adapted to be turned and forced be- 100 105 110 115 120 125 130

low the chime so as to force the disk against said flange.

2. In a receptacle, the combination of a body having an inwardly projecting flange at one end and a reinforcing chime constituting a continuous shoulder parallel to the flange and spaced apart therefrom, a closure of less diameter than the chime resting on the flange, a series of pins projecting upwardly from said closure, and a fastening device revolvably mounted on each pin and comprising a cylindrical body substantially tangential to the closure and a circumferen-

tial wedge connected to said cylindrical body with its ends so disposed that it may be positioned entirely within the circumference of the closure but is adapted to be turned and forced below the chime to force the disk against said flange. 15

In testimony whereof I have signed this 20 specification in the presence of two subscribing witnesses.

EDWARD W. STODDARD.
